(21) Appl. No.: **29/340,208**

The ornamental design for a twin-flap double opening shoulder bag, as shown and described.

(22) Filed: **Jul. 15, 2009**

DESCRIPTION

(51) **LOC (9) Cl.** **03-01**

FIG. 1 is a perspective view of the twin-flap double opening shoulder bag of the present invention;

(52) **U.S. Cl.** **D3/232**

FIG. 2 is a front elevational view of the bag of FIG. 1;

(58) **Field of Classification Search** D3/232–233,
D3/240–246, 318, 324, 286–287; 150/100,
150/103–110, 113–114, 118–119

FIG. 3 is a first side elevational view of the bag of FIG. 1;

See application file for complete search history.

FIG. 4 is a rear elevational view of the bag of FIG. 1;

(56) **References Cited**

FIG. 5 is a second side elevational view of the bag of FIG. 1,
showing the opposite side from that of FIG. 3;

U.S. PATENT DOCUMENTS

FIG. 6 is a top plan view of the bag of FIG. 1; and,
